(57) **CLAIM**

The ornamental design for a quick-lock for pole handle, as shown and described.

DESCRIPTION

FIG. 1 is a perspective view of a first embodiment of a quick-lock for pole handle showing our new design.

FIG. 2 a right side elevational view thereof.

FIG. 3 is a left side elevational view thereof.

FIG. 4 is a top plan view thereof.

FIG. 5 is a bottom plan view thereof.

FIG. 6 is a perspective view of the quick-lock for pole handle shown in FIG. 1, with the quick-lock for pole handle in a retracted configuration.

FIG. 7 is a perspective view of a second embodiment of a quick-lock for pole handle showing our new design.

FIG. 8 a right side elevational view thereof.

FIG. 9 is a left side elevational view thereof.

FIG. 10 is a top plan view thereof.

FIG. 11 is a bottom plan view thereof; and,

FIG. 12 is a perspective view of the quick-lock for pole handle shown in FIG. 7, with the quick-lock for pole handle in a retracted configuration.

The broken lines in the drawings are for the purpose of illustrating portions of the pole handle and form no part of the claimed design.
